AUXILIARY A.C. GENERATOR MOUNTING BRACKET FOR VEHICLE ENGINES

Douglas W. Neill, 200 S. Washington Blvd.,
Sarasota, Fla.

Filed Aug. 27, 1965, Ser. No. 86,746

Term of patent 14 years

(Cl. D54—1)

FIG. 1

FIG. 2

FIG. 3

FIG. 1 is a front perspective view of an auxiliary A.C. generator mounting bracket for vehicle engines showing my new design.

FIG. 2 is an end elevational view thereof.

FIG. 3 is a side elevational view opposite the side shown in FIG. 1.

The broken line showing is for illustrative purposes only.

I claim:

The ornamental design for an auxiliary A.C. generator mounting bracket for vehicle engines, substantially as shown and described.
